UNITED STATES PATENT OFFICE.

FERDINAND W. KROGH, OF SAN FRANCISCO, CALIFORNIA.

CENTRIFUGAL PUMP.

1,117,861.

Specification of Letters Patent.

Patented Nov. 17, 1914.

Application filed July 14, 1910. Serial No. 572,027.

To all whom it may concern:

Be it known that I, FERDINAND W. KROGH, of San Francisco, California, have invented certain new and useful Improvements in 5 Centrifugal Pumps, whereof the following is a specification.

This invention relates more particularly to devices for balancing the weight of the impeller and shaft, and, where the pump 10 is driven by a motor, the armature of the motor, of a centrifugal pump.

In carrying out the invention I provide the pump with a suction chamber, preferably opposite the intake. This suction chamber 15 connects with independent centrifugal arms, arranged between the regular impeller arms of the pump, which draw from it and create the suction therein, except when cut off from connection therewith by the action 20 of a valve whose operation depends upon the movement of the pump impeller in its case.

The details of the invention, and the particular manner in which I have found it 25 best to embody it, will be best understood from the accompanying two sheets of drawing and the description thereof which follows. But it must be understood that the drawings and description are illustrative 30 rather than specific, and that the invention is not to be limited except as set forth in the claims at the end hereof.

In the drawing:—Figure 1 is an elevation of a pump, partly in section to 35 show interior structure, and shows the impeller in its casing, the shaft and motor, the whole being mounted in a frame by which it may be handled. Fig. 2 is a view on an enlarged scale, showing in sectional 40 elevation the impeller and casing and contiguous parts. Fig. 3 is a plan view of the impeller, one half being in section.

In the figures:—1 is a frame in which the various parts are mounted, and which maintains their relation to one another.

2 is a vertical shaft, upon which is mounted the armature 3 of a motor of which 4 represents the field and 5 the casing inclosing it.

50 6 is a second shaft, alined with the first one 2, and rotatably connected therewith by a suitable coupling 7. Shaft 6 is below shaft 2 and supports the weight thereof, for which purpose their ends meet in the coupling. 55 At the lower end of shaft 6 is an impeller 8 in a casing 9, of which 10 is the intake, and

11 the discharge. In the casing, above the impeller chamber, is a suction chamber 12. The impeller 8 is provided with the usual arms 13, by which the liquid to be pumped 60 is drawn from the intake and forced through the outlet. The impeller is also provided with secondary or independent arms 14 which communicate with the space above the impeller by the ports 15, and thereby 65 draw liquid from the suction chamber 12 and force it out of the discharge. The impeller is also provided with a cylindrical flange 16, outside of the ports 15, which extends up into the space which the chamber 70 12 occupies.

17 is a cylindrical flange in the chamber 12, extending downward toward the impeller inside the flange 16 thereof and closely contiguous thereto so as to form a running 75 joint therewith. At the lower edge of flange 17 is an annular inwardly projecting flange 18 which registers immediately above the ports 15 and operates as a valve to close the same when the impeller is drawn upward 80 the desired extent by the suction in chamber 12. The impeller is of the type which comprises spiral arms between two diaphragms; the upper diaphragm "a" registers with the opening into chamber 12 through the 85 flange 18 and coacts therewith in regulating the position of the impeller. The leakage which comes from the discharge of the pump and finds its way between the two flanges 16 and 17, together with leakage from 90 the stuffing box above, will prevent the impeller being drawn up to a degree that would cause an undue friction between the movable and stationary parts.

In operation the impeller naturally tends 95 toward the intake owing to the sucking action of the latter and the weight of the shaft, armature, &c., and the wheel itself. This movement opens the ports 15, and the auxiliary impelling arms 14 then suck from the 100 chamber 12, and, owing to the proportions of the various parts, thereby cause the impeller to move upward. This movement brings the ports 15 against the flange 18, which closes them, and the wheel floats in 105 that position till the leakage relieves the vacuum in the chamber, and the wheel moves away from it to repeat the operation.

At 19 is a pressure chamber in the casing 9, under the impeller, and opposed to the 110 chamber 12. This chamber 19, being open to the discharge is always under pressure,

and tends to raise the impeller. Thus it co-acts with the suction chamber 12 in opposing the downward tendency of the latter.

Surrounding the shafts 2 and 6 are oil reservoirs 20 rotatably connected therewith below the bearings; 21 are stationary oil receiving cups also surrounding the shafts above the bearings and connected to the oil reservoirs by means of pipes 22 through which the oil is carried by centrifugal forces from the reservoirs into the receiving cups and therefrom drip in the bearings by gravity, thus oiling the same automatically.

Having thus described my invention, what I claim is:—

1. In a centrifugal pumping apparatus of the vertical type in combination with the impeller thereof and its casing, a suction chamber in the casing, surrounding the shaft 20 of the impeller opposite the intake and provided with an inwardly projecting flange having a central aperture, impelling arms provided with ports communicating with said aperture and a diaphragm on said arms 25 to regulate said communication.
2. In a centrifugal pumping apparatus of the vertical type in combination with the impeller and casing, a cylindrical flange in the casing projecting downwardly and inwardly from the edge thereof, and forming a suction chamber opposite the impeller, impelling arms provided with ports communicating with said chamber, and a flange on said impelling arms projecting around 35 said cylindrical flange in the casing and forming a running joint.
3. In a centrifugal pumping apparatus, in combination with the impeller and casing, a suction chamber adapted to draw the impeller toward one side of the casing, impelling arms communicating with said chamber.

ber, a flange within said chamber projecting inwardly from the edge thereof to provide means for varying the opening from said chamber to said arms with the lateral 45 play of the impeller.

4. In a centrifugal pumping apparatus, in combination with the impeller and casing, a suction chamber at one side of the casing impelling arms communicating with 50 said chamber, a cylindrical flange on the casing in said chamber, and an annular inwardly projecting flange on the edge of said cylindrical flange, said annular flange in register with the ports from the chamber into the arms and adapted to vary the opening into the same with the lateral play of the impeller.

5. In a centrifugal pumping apparatus, in combination with the impeller thereof and 60 its casing, a cylindrical flange projecting from the casing toward the side of the impeller and forming a suction chamber, an annular inwardly projecting flange on the edge of said cylindrical flange, impelling 65 arms provided with ports communicating with the suction chamber and adapted to be closed by said inwardly projecting flange.

6. In a centrifugal pumping apparatus, of the vertical type, in combination with the 70 impeller thereof and its casing, an open suction chamber in the casing above the impeller and opposite the intake, and impelling arms having a diaphragm adapted to close said chamber.

In testimony that I claim the foregoing I have hereto set my hand this 9th day of July, 1910, in the presence of witnesses.

FERDINAND W. KROGH.
